ELECTROMAGNETIC RELAY

Carl H. Larson, Elkhart, Ind., assignor to The
Adlake Company, a corporation of Illinois

Application June 1, 1936, Serial No. 82,854

8 Claims. (Cl. 200—97)

It is very difficult in electro-mechanical relays to operate a series of electrical contacts at different time intervals after the happening of a particular event, as for example the energizing of the relay coil, and usually it is necessary to employ complicated dash-pot arrangements or clock work in order to accomplish the desired action. The weight, size, cost and maintenance of such relays are obviously serious drawbacks, and the principal object of this invention is to provide simpler, more reliable, more durable and less expensive means for accomplishing the desired results.

More specifically, it is among the objects of this invention to provide a device in which all moving parts are enclosed within a hermetically sealed casing; in which the timing action when once adjusted is constant and unchanged; in which the contacts are capable of carrying heavy loads and standing up under long periods of service; and in which the contacts may be subject to relatively large differences in time delay action.

Further and other objects and advantages will become apparent as the disclosure proceeds and the description is read in conjunction with the accompanying drawings, in which:

Fig. 1 is a partially diagrammatic view of a relay made in accordance with this invention, the parts being shown in the position which they occupy immediately after the control switch has functioned and before the main switch has had an opportunity to function.

Fig. 2 is a view showing the position of the switch parts immediately after the armature has been drawn downwardly within the switch envelope;

Fig. 3 is a view corresponding to Fig. 1, but in this view, the parts are shown in the position which they occupy immediately after the control switch has been energized and before the armature of the main switch has had an opportunity to be restored to its normal position.

Fig. 4 shows a modified form of the invention in which the time delay electrodes are responsive to the outside mercury level, and in which the control switch is made a part of the main switch

Fig. 5 is a fragmentary view showing the relationship of the electrodes to the mercury level at the instant when the central electrode comes in contact with the mercury;

Fig. 6 shows the armature in its upper position after the central or control electrode has recycled the switch;

Fig. 7 is a fragmentary, sectional view of a modified form of the invention; and

Fig. 8 is a fragmentary, sectional view taken on the line 8—8 of Fig. 7.

For the purpose of complying with section 4888 of the Revised Statutes, several preferred embodiments of the invention have been disclosed in conjunction with an electrically illuminated advertising sign. It will be understood, however, that the specific embodiments of the invention chosen for description and illustration are merely examples of the many ways in which the invention herein disclosed may be embodied within the scope of the appended claims. The claims, therefore, are to be construed as broadly as the prior art will permit.

Assuming the advertising sign to be controlled consists of three units, for example "A & W", it is possible to operate the sign (among other ways) by first illuminating the letter "A", then "&" and finally "W", after which all three units are extinguished, ready for the sequence to be repeated, or the three units may be illuminated simultaneously and then the "A" extinguished, then "&" and finally "W".

The main switch 10 and control switch 11 shown in Figs. 1 and 3 are capable of accomplishing the first alternate and the switch shown in Figs. 4, 5, and 6 is capable of accomplishing the second alternate.

Referring now to Fig. 1, the sign units are indicated at 12, 13 and 14, and each has a lead connecting through a conductor 15 with one side, for example the negative side, of a battery or other source of electro-motive force 16. Conductors 17, 18 and 19 leading from the respective units, are connected, respectively, to electrodes 20, 21 and 22 which are sealed through the base of a mercury switch envelope 23 which contains a quantity of mercury 24, a mercury displacer, generally designated 25, and an inert gas fill indicated at 26, the latter being introduced into the envelope after it has first been evacuated. Preferably, the envelope 23 is made of a boro-silicate glass, such as 733A made by the Corning Glass Works of Corning, New York, and the electrodes 20, 21 and 22 are preferably of molybdenum.

A lead 27 from the relay coil 28 associated with the control switch 11 is connected to another electrode 29 similarly sealed through the base of the switch envelope, and all four electrodes 20, 21, 22 and 29 are insulated from each other and from the mercury fill by one or more glass sleeves 30. Preferably, short sections of ceramic tubing 31 are fused to the tops of the sleeves 30 leaving the ends of the electrodes exposed at different heights with respect to the base of the

envelope, these exposed portions being indicated at 32, 33, 34, and 35. The ceramic material 31 serves the purpose of resisting the deteriorating effect of the electric arc formed when the switch 5 is carrying a comparatively heavy load.

The displacer 25, which is shown more or less diagrammatically, comprises an iron sleeve 36 vertically slotted as indicated at 37 and having an opening in its upper wall into which a glass 10 thimble 38 is fitted and held in place by a spring 39 tightly coiled over the projecting end of the thimble. Other means, may, of course, be employed for holding the thimble within the sleeve 36.

15 The thimble 38 is preferably made of 733A glass and has a relatively small opening 40 into which a plug 41 of ceramic material is fused. When 733A glass is used for the thimble 38, the 20 ceramic material is preferably Alundum (Grade RA 84, RA 360 or RA 98) a product of the Norton Company, Worcester, Massachusetts, as this material fuses readily with 733A glass.

In order to give the displacer greater buoyancy, a ceramic liner 42 may be provided in the 25 lower end of the displacer, and a spring 43 tightly coiled on the projecting end of the liner serves to hold the liner in place and protect the switch envelope.

20 The switch 10 is operated by a relay coil 44 having an iron circuit 45 associated with it which includes pole sleeves 46 and 47 separated by an air gap which in this case is occupied by a split sleeve 48 of non-magnetic material. The sleeve 48 has sufficient resiliency to grip the tube 23 and 25 hold it in adjusted position.

25 The coil 44 associated with the switch 10 is connected by conductors 49 and 50 with the electrodes 51 and 52, respectively, of the control switch 11, the latter being a mercury switch of 30 the same general type as the main switch 16, and comprising a switch envelope 53, a mercury fill 54, a displacer 55, the upper portion 56 of which is of magnetic material, and the lower portion 57 of which is in the form of an impervious glass 35 thimble which displaces a sufficient amount of mercury when the displacer is in its lowermost position to cover the bared end 58 of the electrode 52, but displaces an insufficient amount of mercury when the displacer is raised by energization of the relay coil 28 to bridge the electrodes 51 and 52 with mercury.

40 Thus, when the relay coil 28, associated with the control switch 11, is de-energized, the main switch coil 44 is energized (a battery 59 or the like being provided for supplying the electromotive force) and when the relay coil 28 is energized, the main switch coil 44 is de-energized.

45 Assuming the parts of the main switch 10 to be in the position in which they are shown in Fig. 1, and that the relay coil 28 associated with the control switch 11 has just been energized, the displacer 25 of the main switch will be drawn downwardly to close the air gap between the pole sleeves 46 and 47 and as this takes place, the thimble 38 will entrap a certain amount of gas and force mercury away from the exposed electrodes 32, 33, 34, and 35 (see Fig. 2). The sign units at this moment are obviously not illuminated. The gas pressure created within the 50 thimble 38, due to the difference of mercury levels within and on the outside of the thimble, causes gas to slowly escape through the porous plug 41 and as the pressure tends to become equalized, the mercury level on the inside of the thimble 55 will slowly rise while that on the outside slowly

falls and after a given time interval has elapsed, depending upon the porosity of the plug 41, the mercury fill, height of the electrodes, etc., the mercury on the inside of the displacer will finally establish an electrical contact between the electrode 32 and the common electrode 60, which is constantly in contact with the mercury. When the circuit through the electrodes 32 and 60 is closed, the sign unit 12 is illuminated. As the mercury level continues to rise, the electrodes 33 10 and 34 are successively placed in electrical connection with the common electrode 60, thus successively illuminating the sign units 13 and 14. When the mercury level reaches the electrode 35, the coil 28 associated with the control switch 15 11 is energized, thereby breaking the electrical circuit through the main switch coil 44, allowing the displacer 25 to rise by buoyancy to the position shown in Fig. 1. The mercury that is carried up within the thimble 38 as the displacer 20 rises, falls away from the thimble as soon as the lower edge of the thimble 38 reaches a point above the outside mercury level. At this instant, the circuit through the electrodes 32, 33, 34 and 35 is broken and the sign units 12, 13 and 14 are 25 extinguished. At the same time, the coil 28 associated with the control switch 11 is deenergized allowing the displacer 25 to fall by gravity to the position shown in Fig. 1, thereby reenergizing the main switch coil 44 and starting the cycle 30 once more.

The position of the switch parts in Fig. 3 is at the instant when the control relay has been energized, thereby breaking the electrical circuit through the main switch coil 44, but before the 35 main switch displacer 25 has had an opportunity to rise to the position shown in Fig. 1.

The relay shown in Figs. 4, 5 and 6 has the control switch incorporated into the main switch, but it will be understood that a separate 40 switch may be used if desired.

The electrodes which control the sign units 12, 13 and 14 are subject to the outside mercury level and are indicated at 70, 71 and 72. They are sealed through the base of the switch 45 envelope 73, together with a central electrode 74 and a common electrode 75. Insulating sleeves, generally indicated at 76 surround the electrodes 70, 71, 72 and 74 for a portion of their height and as before, ceramic sleeves cap the glass 50 sleeves 76 to better withstand the ravages of the electric arc when the circuits are being opened and closed.

The switch envelope 73 may be provided with a vertical protuberance 77 to accommodate the electrodes 70, 71 and 72, and a displacer 78 is reciprocable within the switch envelope in response to a relay coil 79 to shift the mercury fill 80, and thereby cover and/or uncover one or more electrodes.

The displacer 78 (shew somewhat diagrammatically) consists of an iron armature 81 telescoped over a glass thimble 82 provided with a porous wall 83 fused into the top wall of the thimble. Guide rings 84 are provided on the displacer to position the armature within the envelope and coil springs 85 hold the rings in place.

An iron circuit, generally designated 86, is associated with the coil 79 and it includes pole sleeves 87 and 88 spaced apart to provide an air 70 gap 89 which the armature 78 tends to span when the relay coil 79 is energized.

The sign units 12, 13 and 14 are connected through a conductor 90 with one side of a battery 91, or other source of electromotive force, 75

and the other side of the battery is connected to the common electrode 75. This latter electrode is also connected through a conductor 92 with the relay coil 78, the other lead 93 from the coil being connected to the central electrode 74 through a battery 84.

When the coil 78 is energized (see Fig. 5) the displacer 78 is immediately lifted to the position shown in Fig. 6 at which time the electrodes 10, 11, 12 and 74 are out of contact with the mercury. Since the latter electrode controls the energization of the coil 78, the action of the displacer in rising to the position shown in Fig. 6 actually de-energizes the coil 78 and it falls by gravity to the position shown in Fig. 4, forcing the outside mercury level immediately above the tallest electrode 10 and at the same time forcing mercury away from the central electrode 74 due to the entrapment of gas within the thimble 82. As gas slowly escapes through the porous plug 83, the mercury level slowly rises within the thimble and at the same time, there is a corresponding lowering of the outside mercury level. Obviously, the fall of the displacer functions to immediately illuminate the entire advertising sign and when the outside mercury level falls below the top of the insulating sleeve surrounding the electrode 10, the unit 12 will be extinguished. Shortly thereafter (the length of time depending upon the porosity of the time delay element 83) the unit 13 will be extinguished and still later, the unit 14. When the unit 14 has been extinguished (but not until then) the mercury level on the inside of the displacer reaches the top of the sleeve surrounding the central electrode 74 and thereby closes the circuit through the coil 78. When this takes place, the displacer 78 is lifted to the position shown in Fig. 6, and since the thimble is lifted completely out of the mercury, the latter falls away quickly from the interior of the thimble, leaving all of the electrodes uncovered whereupon the switch repeats its cycle.

It will be understood that the length of the time interval between the opening and/or closing of the several circuits may be varied within relatively large limits by proper selection of the mercury fill, height of insulating sleeves, and the material used for the time delay element. When it is desired to have the electrodes subject to greater selection and still greater range of time control, an arrangement such as shown in Figs. 7 and 8 (by way of illustration) may be used.

As shown in Fig. 7, a plurality of electrodes 100, 101, 102, 103 and 104 may be sealed through the base of a switch envelope 105, each being provided with an insulating sleeve, such as indicated at 106. The electrodes are formed so that their ends are arranged as shown in Fig. 8. The central electrode 102 supports a molded ceramic time delay element, generally designated 107, which has a central pocket 108 and a plurality of radial chambers 109, each of which receives one of the electrodes.

An iron armature 110 moving in response to a coil shifts the mercury level so as to close the bottom of the element 107 with mercury and establish a pressure differential between the interior of the element and the exterior. The rate of gas flow between the several chambers of the time delay element 107 may be controlled by the relative sizes of the chambers, the material used for the individual chambers, by applying dabs of cement to portions of the time delay element 75 to vary the porosity of that particular portion

of the element, or by other suitable means. Also the relative effective time delay between the several electrodes may be controlled by properly selecting the height of the insulating sleeves 106. By way of example, the sleeve around the electrode 100 is longer than that around the electrode 103, so that if the chamber associated with the electrode 103 is identical with the one associated with the electrode 100, the latter will not make contact with the mercury until after the electrode 103 has made contact.

It is, of course, understood that in the specific illustrations of Fig. 7, each of the insulated electrodes completes its respective circuit through a common electrode 111.

One of the outstanding advantages of this invention is the great number and variety of time delay effects which may be introduced into a single relay. Obviously, therefore, the invention may be variously embodied within the appended claims.

Instead of having the relay coils lower the displacers, the switches may be built so that the coils lift the armatures and gravity lowers them.

I claim:

1. In a mercury switch relay, a relay coil, a switch associated with the coil comprising a switch envelope, a plurality of electrodes in the envelope, a mercury fill, means responsive to the coil for shifting the fill into contact with, or out of contact with, at least two of said electrodes, depending on the direction of movement of the fill and time delay means for retarding the movement of at least a portion of the mercury fill in the vicinity of said two electrodes, said time delay means and said two electrodes cooperating to effect successive like changes in the electrical contact relationship between the fill and said two electrodes.

2. In a mercury switch relay, a relay coil, a mercury switch associated with the coil comprising a switch envelope, a plurality of electrodes in the envelope, a mercury fill, means responsive to the coil for shifting the fill in a given direction and time delay means in the envelope associated with two of the electrodes and adapted to effect successive like changes in the electrical contact relationship between the fill and said two electrodes when the fill is shifted in said direction.

3. In a mercury switch relay, a relay coil, a mercury switch associated with the coil including a plurality of electrodes and a quantity of mercury adapted to be moved to and from contact with said electrodes, and means for delaying the movement of at least a portion of the mercury whereby the like condition of the electrical circuits through two of the electrodes and a third electrode in the switch is successively changed to other like conditions after the lapse of a given time interval from the operation of the relay coil.

4. In a mercury switch relay, a relay coil, a switch associated with the coil comprising a switch envelope, a plurality of electrodes in the envelope, a mercury fill, a magnetically responsive displacer for shifting the fill to change the condition of the electrical circuits through two of said electrodes and a third electrode in the switch, and time delay means telescoped over said two electrodes for retarding the movement of at least a portion of the mercury fill in the vicinity of said two electrodes, said means and said two electrodes cooperating to effect successive changes in the condition of said circuits.

5. In a mercury switch relay, a relay coil, a switch associated with the coil comprising a

switch envelope, a plurality of electrodes in the envelope at different heights with respect to the envelope base, a mercury fill, means responsive to the coil for shifting the fill to change the condition of the electrical circuits between two of the electrodes and a third electrode in the switch, and time delay means associated with said two electrodes for retarding the movement of at least a portion of the mercury fill in the vicinity of said two electrodes whereby successive changes in the condition of the respective circuits are effected.

6. In a mercury switch relay, a relay coil, a switch associated with the coil comprising a switch envelope, a group of electrodes in the envelope at different heights with respect to the envelope base, a mercury fill means instantaneously responsive to the coil for shifting the fill to change the condition of the electrical circuits between two of the electrodes and a third electrode in the switch, and time delay means associated with said two electrodes for retarding the movement of a portion of the fill in the vicinity of said two electrodes whereby successive changes in the condition of said respective circuits controlled by said two electrodes are effected.

7. In a mercury switch relay, a relay coil, a mercury switch associated with the coil including a switch envelope, a group of electrodes, and a quantity of mercury adapted to be moved to and from contact with said electrodes, and means

for delaying the movement of at least a portion of the mercury whereby the like condition of the electrical circuits through two of the electrodes and a third electrode in the switch is successively changed to other like conditions for the lapse of a given time interval from the operation of the relay coil, said means including a gas restricting element telescoped over the exposed portions of the electrodes and provided with a plurality of separate pockets each of which receives one electrode, each pocket being provided separately with means for restrictively passing gas between the interior of the pocket and the chamber surrounding the pocket at a predetermined rate of speed.

8. In a mercury switch relay, a relay coil, a switch associated with the coil including a switch envelope, a plurality of electrodes in the envelope at different heights with respect to the envelope base, a mercury fill, a displacer surrounding the electrodes being responsive to the coil for shifting the fill to change the condition of the electrical circuits between two of the electrodes and a third electrode in the switch, and time delay means fixed with respect to the displacer and associated with said two electrodes for retarding the movement of at least a portion of the mercury fill in the vicinity of said two electrodes whereby successive changes in the condition of the respective circuits are effected.

CARL H. LARSON.
